UNITED STATES PATENT OFFICE.

WILLIAM C. HUSS, OF CINCINNATI, OHIO.

DESIGN FOR A WALL-FIXTURE FOR COUNTERS.

SPECIFICATION forming part of Design No. 30,960, dated June 6, 1899.

Application filed February 29, 1896. Serial No. 581,400. Term of patent 7 years.

To all whom it may concern:

Be it known that I, WILLIAM C. HUSS, a citizen of the United States, and a resident of Cincinnati, in the county of Hamilton and 5 State of Ohio, have invented a certain new and useful Design for a Wall-Fixture for Counters, of which the following is a specification.

My invention is a new design for back bar 10 or wall-fixture for counters. Its distinguishing features are the serpentine architrave, the massive romanesque columns supporting the same from the floor at each end of the side-board portion, the intermediate columns, also 15 resting upon the floor and supporting the architrave, the end columns resting upon the architrave and supporting the cornice, the intervening pilasters between the architrave and cornice, and the ornamentation embellishing the fixture, as shown in the accompanying drawings, in which—

Figure 1 is a vertical transverse sectional view of the back fixture, looking from the broken-away portion of Fig. 2 toward the end 25 of the fixture. Fig. 2 is a front elevation of one end of the fixture.

The sideboard portion A is of ordinary construction, except that it is divided intermediate by the base of the columns B, against 30 which the divided portions of the sideboard abut. Each end of the architrave C rests upon massive columns D, which extend from the floor-line up to the architrave. The shaft of this column is formed in a cluster and is 35 highly polished, differing in shade from the capital d and base d', and is centrally encircled by a paneled belt d² of different color from the shaft. The column is what might be termed "romanesque," the lower part of 40 the capital being finished in foliage and the upper part in grotesque or fantastic masks or heads.

At the end of the fixture is a fantastic ornament E, the upper part of which represents 45 a female figure depending by one hand from a ring connected to the architrave, the other hand holding up a torch e, from which

branches foliage and globes. The lower part of the body terminates in foliage, the scroll end of which is connected to the band d². 50

The architrave projects out in a bold swell c at each end and in convex curves less pronounced at c' centrally between the columns B and D, the short concave curve between the end column and the convex curve c' being indicated by the vertical shaded lines and the lower portions of the architrave being immediately above the columns B. The upper molding c² of the architrave at the ends conforms to the base of the columns F, which 60 support the cornice G at the ends, and the architrave at the end is finished by a round corbel c³, which is embellished with a head in low relief and foliage, which extends around it and over upon the face of the serpentine molding. The columns F are what might be termed "three-quarter" columns, lapping around the corner of the end projections H of the frieze. In the back of the frieze are reflecting panels or mirrors I, which are framed by the end 70 projections H, the pilasters h, and the lower moldings of the cornice and frieze. The columns F and their capitals are also formed in clusters and of very dark material to form a pleasing contrast to the reflecting-surfaces of 75 the frieze and the lighter cornice and architrave. The shaft of column B is also formed in clusters, and, like the shaft of the column D, it is surmounted by a grotesque capital, and the straight shaft rests upon a base carved 80 in the same style, the grotesque masks being in the middle and terminating above and below in foliage, the corner of the dado being embellished with fantastic foliated heads. The upper cap is surmounted by an abacus, 85 which is a return of the lower molding of the architrave, and above it, on the face of the architrave, is a carved pilaster c⁴, which is surmounted by a carved abacus, which is a return of the upper molding c² of the architrave. Above these intermediate columns and in front of the frieze is a foliated vase J, 90 from which springs a romanesque ornament consisting of a central shaft supporting a

carved dish-shaped ornament and foliated branches upon each side terminating in an animal's head and feet, the feet of the animal resting upon a foliated scroll that turns back 5 and rests upon the upper edge of the vase.

The front of the architrave, pilaster *h*, and the projections *H* are each decorated with romanesque foliage in low relief. The back 10 of the fixture below the architrave and above the sideboard portion is a mirror or mirrors

K, the end frames *k* of which above the sideboard top are beaded.

What I claim is—

The design for a wall-fixture for counters substantially as shown and described.

WILLIAM C. HUSS.
